US0D1099370S

(12) **United States Design Patent** (10) **Patent No.:** **US D1,099,370 S**
(45) **Date of Patent:** **** Oct. 21, 2025**

(54) **CEILING PANEL**

(71) Applicant: **Turf Design, Inc.**, Gilberts, IL (US)

(72) Inventors: **Jason T. Gillette**, Chicago, IL (US);
Keith Alsberg, Evanston, IL (US);
Scott H. Wilson, Chicago, IL (US);
David B. Seal, Chicago, IL (US)

(73) Assignee: **Turf Design, Inc.**, Gilberts, IL (US)

(**) Term: **15 Years**

(21) Appl. No.: **29/949,123**

(22) Filed: **Jun. 25, 2024**

Related U.S. Application Data

(63) Continuation of application No. 18/376,326, filed on Oct. 3, 2023, which is a continuation of application No. 17/530,230, filed on Nov. 18, 2021, now Pat. No. 11,773,591, which is a continuation of application No. 16/887,373, filed on May 29, 2020, now Pat. No. 11,180,916, which is a continuation of application No. 16/539,673, filed on Aug. 13, 2019, now abandoned, which is a continuation of application No. 16/006,547, filed on Jun. 12, 2018, now Pat. No. 10,407,904.

(57) **CLAIM**

The ornamental design for a ceiling panel, as shown and described.

DESCRIPTION

FIG. 1 is a perspective view of a ceiling panel showing our new design;

FIG. 2 is a top plan view thereof;

FIG. 3 is a side elevation view thereof; and,

FIG. 4 is a front elevation view thereof.

The broken lines illustrate portions of the ceiling panel that form no part of the claimed design.

1 Claim, 1 Drawing Sheet
